UNITED STATES PATENT OFFICE

LOUIS A. GEBHARD, OF WASHINGTON, DISTRICT OF COLUMBIA, ASSIGNOR TO WIRED
RADIO, INC., OF NEW YORK, N. Y., A CORPORATION OF DELAWARE

TRANSMITTING SYSTEM

Application filed December 22, 1928. Serial No. 327,983.

My invention relates broadly to transmitting systems and more specifically to transmitting systems employing water cooled thermionic tubes.

5 One of the objects of my invention is to provide certain improvements in water cooled thermionic tube systems by providing means for preventing loss of high frequency signaling energy.

10 Another object of my invention is to provide an efficient method for preventing the loss of high frequency signaling energy in the cooling system employed in thermionic tube signaling systems.

15 Other and further objects of my invention will be apparent from the specification hereinafter following by reference to the accompanying drawing which diagrammatically shows the transmitting system of my invention.

20 In high power transmitting systems and rectifying systems employing thermionic tubes, it is frequently desirable to employ tubes that have their anodes cooled by a circulation of liquid. When thermionic tubes, having water cooled anodes, are employed in high frequency signaling systems it is desirable to insulate the anodes from the cathode or ground potential. This is usually accom-
25 plished by employing coils of rubber tubing for conducting the circulating liquid to and from the thermionic tube. This provides a high resistance in parallel with the source of anode potential where the negative terminal is connected to the cathode and ground.

30 The positive polarity of the source of anode potential is connected to the anode of the thermionic tube through a radio frequency choke coil. This radio frequency choke coil
35 may have a comparatively low direct current or low frequency resistance while operating effectively as a choke to the high frequency energy. When such an arrangement is employed, some high frequency energy will be

40 present in the rubber insulating hose coil which conducts the circulating liquid to and from the thermionic tube. It is an object of my invention to exclude such high frequency energy from the insulating hose coil thereby
45 preventing undue loss of energy and reduc-

ing the resistance to the potential supplied the anode. By excluding high frequency energy from the insulating hose coil, danger of high frequency potential break-down between adjacent turns of the coil is prevented. This potential break-down in the hose coil
55 interrupts the circulation of the cooling liquid and causes the entire system to be inoperative. In the transmitting system of my invention the foregoing disadvantages are
60 overcome.

55 In the accompanying drawing, a source of signaling energy 1 is associated with a water cooled thermionic tube 2. Energy is transferred from source 1 to the grid connection 5 of thermionic tube 2 by means of capacity 6. Cathode connections 3 are supplied with a source of energy from an alternating current supply 4 reduced to the proper value by transformer 18. The electrical center of the cathode supply winding of transformer 18 is connected to ground 10. High frequency inductance 12 is connected to thermionic tube receptacle 2a through capacity 11. Thermionic tube receptacle 2a
65 is of the same potential as the anode potential of thermionic tube 2. A source of energy 9a supplies the proper operating potential to grid connection 5 through resistance 7 and high frequency choke coil 8. A source of energy 9b is connected with the anode of thermionic tube 2 by means of metal tubing 14-14a and receptacle 2a. A common connection 9 to ground 10 provides a cathode return circuit for sources of energy 9a and
70 9b. Coils of metal tubing 14 and 14a are provided as conductors for the circulating cooling liquid to and from receptacle 2a. Coils 14 and 14a serve effectively as high frequency choke coils excluding high frequency energy from insulating hose coils
75 22-22a and source of cooling liquid 21. Coils 14 and 14a have a low resistance to the supply of energy from source 9b to the anode of thermionic tube 2 and are sufficient
80 to offer a low resistance to the circulation of the cooling liquid. A capacity 16 is provided, conducting the low potential high frequency energy to the ground or cathode circuit. Capacity 16 is a further protection
85 100

to prevent high frequency energy from reaching hose coils 22—22a and source 21, which may be omitted when coils 14 and 14a are of the proper design.

3. It is obvious that any combination of coils may be employed in the cooling system. For instance coil 14a may be omitted and coil 14 employed. In such an arrangement coil 14 could be of suitable reactance to prevent 10 high frequency energy from reaching the source of cooling liquid. A connection 15 is provided between the low potential ends of coils 14 and 14a thereby reducing resistance to the supply of anode potential to thermionic tube 2 from source 9b. Coils 14 and 14a may be constructed of copper tubing or any suitable metal. It is possible to connect the source of anode potential to 2a providing a suitable high frequency choke coil is 20 employed in series. In the latter modification, coils 14 and 14a need not be of a low resistance to the source of anode potential. This allows considerable choice of metals and alloys thereof, that are effective high 25 frequency choke coils but have a direct current resistance or low frequency resistance of too great a value to be employed in the series arrangement heretofore mentioned. When extremely high frequencies are employed it 30 is obvious that coils 14 and 14a may be of straight tubing and not formed in the coil arrangement illustrated in the accompanying drawing. A load circuit 10, 12 and 13 is illustrated in the accompanying drawing. 35 It is obvious that additional amplifiers may be employed of similar arrangement to that shown in the accompanying drawing.

While I have described my invention in certain of its preferred embodiments, I desire 40 that it be understood that modifications may be made and that no limitations upon my invention are intended other than those imposed by the scope of the appended claims.

What I claim as new and desire to secure 45 by Letters Patent of the United States is as follows:

1. A transmitting system employing thermionic tubes having the anode electrode cooled by a circulating liquid, a coil of metallic tubing connected with the anode electrode of said thermionic tube for conducting the cooling liquid to the anode of said tube while excluding high frequency energy from the source of said liquid and separate means 55 connected with said tubing for dissipating heat from the cooling liquid.

2. In a transmitting system employing thermionic tubes adapted to have the anodes thereof cooled by a circulating liquid, a coil of metallic tubing for conducting the circulating liquid to and from said thermionic tube, said coil of metallic tubing having sufficient reactance for effectively preventing high frequency energy from reaching the source of said circulating liquid and separate

cooling coils connected in series with said metallic tubing for radiating heat from the circulating liquid.

3. In a transmitting system employing thermionic tubes having the anodes thereof cooled by a circulating liquid, a coil of metallic tubing for conducting the circulating liquid to and from the anodes of said thermionic tubes said tubing having such dimensions as will offer a high effective resistance to high frequency electrical energy while conducting the anode potential to said tube and a heat dissipating coil connected with said coil of metallic tubing radiating heat from said circulating liquid. 75

4. In a transmitting system employing thermionic tubes having the anodes thereof adapted to be cooled by a circulating liquid, coils of metallic tubing for conducting the circulating liquid to and from said thermionic tubes, said coils having a high impedance to high frequency energy and coils of insulation material connected in series with the first mentioned coils for conveying the circulating liquid to said first mentioned coils while dissipating the heat therefrom. 85

5. In a transmitting system employing thermionic tubes having the electrodes thereof cooled by a circulating liquid, a plurality of coils of metallic tubing connected with the anodes of said tubes, said coils offering a low resistance to potentials supplied to said anodes while presenting a high impedance to high frequency energy developed in circuits connected with said anodes and coils of insulation material connected in series with said first mentioned coils for conveying cooling water thereto. 95

6. In a transmitting system employing thermionic tubes, a thermionic tube having the anode thereof cooled by a circulating liquid, coils of tubing for conducting said liquid to the anode of said thermionic tube, said coils having a low resistance to the circulation of said liquid and a high impedance to high frequency electrical energy existent on said anode, and auxiliary means connected with said coils of tubing for dissipating the heat from said circulating liquid. 105

7. In a transmitting system a thermionic tube having associated control and energizing circuits, means for cooling the anode of said tube by a circulation of liquid and a coil for conducting the cooling liquid to the anode of said tube said coil having a low electrical resistance to low frequency and direct current energy and a high impedance to high frequency signaling energy and a coil of insulation material connected with said aforementioned coil for conveying the cooling liquid therefrom while dissipating the heat therein. 115

8. In a transmitting system a thermionic tube having the anode thereof adapted to be cooled by a circulating liquid, a metallic con-

ducting member for the circulating liquid, said member offering a low resistance to low frequency electrical energy and high impedance to electrical energy of high frequency 5 and an insulated conducting member connected with said metallic conducting member and providing a path for the circulating liquid therethrough while radiating heat from the circulating liquid.

10. In a transmitting system employing thermionic tubes a high power thermionic tube having an anode adapted to be cooled by a circulating liquid, a conducting member for said liquid, said member having a low 15 electrical resistance to direct current and a high impedance to high frequency signaling energy and an auxiliary conducting member connected with said aforementioned conducting member and having substantially infinite 20 resistance to the passage of electrical energy while dissipating the heat from the circulating liquid.

10. In a transmitting system employing thermionic tubes, a high power thermionic tube having an anode adapted to be fluid cooled, means for causing a cooling fluid to circulate to and from the anode of said thermionic tube, a member included in said means having a low resistance to the circulation of 25 said liquid and electrical energy of low frequency value and having a high impedance to high frequency signaling energy and an auxiliary member connected with said means comprising tubing of insulating material 30 having infinite resistance to electrical energy 35 for dissipating the heat in said cooling fluid.

11. A transmitting system including a high power tube having a cathode, a control electrode and an anode, an oscillating circuit 40 connected with said anode, a control circuit connected with said control electrode, means for energizing said cathode, a power supply circuit for said anode, a fluid circulating system for subjecting said anode to the effects 45 of cooling fluid, said fluid circulating system including a supply pipe line and a discharge pipe line leading to said anode, a pair of independent sets of coils, one set of said coils consisting of metallic tubing wound in 50 the form of inductances with adjacent ends thereof connected to the power supply circuit for said anode for subjecting said anode to high potential through the circuit formed by the metallic tubing, the other set of said 55 coils consisting of insulation material connected in series with said aforesaid coils for dissipating heat in the fluid path to said 60 foresaid coils while radio frequency currents from said oscillation circuit are prevented from reaching said fluid circulating system by the reactance offered by said first 65 mentioned coils.

12. In a high power transmission system, a high power electron tube having an anode 65 adapted to be cooled by a circulating fluid,

sets of independent pairs of coils, one set of said coils being formed by conductive tubing wound in the form of radio frequency choke coils and providing a circuitous path for the cooling fluid from said anode while conductively applying high potential to said anode, the other set of said coils being formed of insulation material, said coils conjointly isolating the source of fluid supply from losses in said transmission system.

13. In a transmitting system including a high power tube having a cathode, a control electrode, and an anode adapted to be fluid cooled, an output coil connected with said anode, a control circuit connected with said control electrode, means for energizing said cathode, a source of power supply for said anode, a pair of metallic tubular coils having inductance of such value as to exclude radio frequency currents of the range of frequencies at which said transmitting system is operated, one of said metallic coils being connected to said anode at the fluid inlet thereof, the other of said metallic coils being connected to said anode at the fluid outlet thereof, said metallic coils being separate from said output coil, said source of anode power supply having its positive terminal connected to both of said metallic coils at the ends thereof remote from said anode and having its negative terminal connected to said cathode, a source of circulating cooling fluid, and a pair of insulating fluid conducting members connected to said source of fluid and respectively to said metallic coils.
